CLAIM

The ornamental design for a vacuum, as shown and described.

DESCRIPTION

FIG. 1 is a front perspective view of a vacuum according to the invention.

FIG. 2 is a front view of the vacuum of FIG. 1.

FIG. 3 is a rear view of the vacuum of FIG. 1.

FIG. 4 is a right side view of the vacuum of FIG. 1.

FIG. 5 is a left side view of the vacuum of FIG. 1.

1 Claim, 8 Drawing Sheets
